US00D572669S

(12) **United States Design Patent**
Jiang

(10) **Patent No.:** **US D572,669 S**
(45) **Date of Patent:** **** Jul. 8, 2008**

(54) **HEAT DISSIPATION ASSEMBLY**

(75) Inventor: **Shih-Jie Jiang**, Kaohsiung (TW)

(73) Assignee: **Asia Vital Components Co., Ltd.**,
Kaohsiung (TW)

(**) Term: **14 Years**

(21) Appl. No.: **29/284,191**

(22) Filed: **Sep. 1, 2007**

(51) LOC (8) Cl. **13-03**

(52) U.S. Cl. **D13/179**

(58) Field of Classification Search **D13/179;**
165/80.3, 104.33, 151, 122, 185; 257/706,
257/707, 718-722; 361/687, 695, 697, 700,
361/702, 704, 709, 710, 711, 719

See application file for complete search history.

Primary Examiner—Selina Sikder

(57) **CLAIM**

The ornamental design for a heat dissipation assembly, as shown.

DESCRIPTION

FIG. 1 is a perspective view of a heat dissipation assembly showing my new design;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a bottom plan view thereof.
